BOBBIN WINDER FOR SEWING MACHINES

Filed Nov. 1, 1935

UNITED STATES PATENT OFFICE

2,055,387

BOBBIN-WINDER FOR SEWING MACHINES

Raymond L. Plumley, Brooklyn, N. Y., assignor to
The Singer Manufacturing Company, Elizabeth,
N. J., a corporation of New Jersey

Application November 1, 1935, Serial No. 47,769

11 Claims. (Cl. 242—20)

This invention relates to bobbin-winders for sewing machines and it has as its primary objects to provide a device of that nature which is simple in construction and therefore inexpensive to manufacture; which readily may be thrown into or out of operation; which may be operated without actuating the sewing mechanism; and which will facilitate removal of the bobbin from the bobbin-holding spindle.

With the above and other objects in view, as will hereinafter appear, the invention comprises the devices, combinations and arrangements of parts hereinafter described and claimed.

The several features of the invention and the advantages attained thereby will be readily understood from the following description in conjunction with the drawing which has been annexed as a part of this disclosure and which depicts a preferred embodiment of the invention.

In the accompanying drawing, Figure 1 is a side elevation of a sewing machine provided with the present improved bobbin-winder. Fig. 2 represents a horizontal sectional view substantially on the line 2—2 of Fig. 1, showing, in full lines, the bobbin-winder in its operative position, and illustrating, in dotted lines, its inoperative position. Fig. 3 represents a sectional view on the line 3—3 of Fig. 1 illustrating the locking device which is adapted to maintain the bobbin-winder in its inoperative position. Fig. 4 is a view similar to Fig. 3 showing the means for locking the bobbin-holding spindle against rotary movement, thereby to facilitate removal of the bobbin therefrom. Fig. 5 is a view similar to Fig. 4, showing a modified form of spindle locking means.

Referring more specifically to the drawing, the invention is disclosed as embodied in a sewing machine having a frame comprising a base 1, a standard 2, a bracket-arm 3 and a head 4. Rotatably journaled in the base 1 is a main or driving shaft 5 adapted to actuate (by connections not shown) the various elements of the stitch-forming and fabric-feeding mechanisms. Motion is transmitted to the shaft 5 by a belt 6 which engages a combined pulley- and hand-wheel 7 adapted to be secured to the shaft 5, by means later to be described. The belt 6 may be driven from any suitable source of power such, for example, as by an electric motor mounted in the base 1, as shown in United States patent to Hohmann, No. 2,012,606, August 27, 1935.

During the operation of the sewing machine, the belt-wheel is secured to the main shaft and drives the latter. As shown in Fig. 2, the connection between the belt-wheel and the shaft is

effected by frictionally clamping the flange portion 7^a of the wheel 7 to an annular clutch-disk 8, the hub of which is secured upon the shaft 5 by a pin 9. This clamping action is provided by a manually rotatable nut 10, threaded upon the end 5^a of the shaft 5 and engaging a washer 11 which, in turn, abuts the hub of the belt-wheel. Rotation of the nut in one direction forces the flange 7^a of the wheel 7 into driving contact with the annular clutch-disk 8 and establishes a drive from the belt-wheel to the shaft 5 to operate the sewing machine. Rotation of the nut in the opposite direction releases the clutch and permits the belt-wheel to rotate idly on the portion 5^b of the shaft 5 for the purpose of winding bobbins, as hereinafter will be more fully described.

The rear end of the shaft 5 is formed with an axial bore 12 providing a chamber adapted to contain lubricant which is transmitted, through radial ducts 13, to that portion 5^b of the shaft on which the hub of the wheel 7 is journaled. Wicking *w* in the bore 12 acts to retain the lubricant and regulate the rate at which it is transmitted to the wheel bearing.

A cap-screw 14, threaded into the end of the bore 12, serves the dual function of holding the lubricant in the bore and of preventing the clamp-nut 10 from being inadvertently removed from the shaft 5.

The bobbin-winder per se comprises a spindle 15 rotatably journaled and axially movable in a bore 16^a formed in a bearing 16 provided by the base 1. One end of this spindle projects through an opening 17 in an end wall 1^a of the base and has secured thereto a disk 18 adapted, in one position of the spindle, to bear against the side of the belt 6 to receive rotary motion therefrom. The end portion 15^a of the spindle beyond the disk 18 is tapered slightly and is adapted to receive and frictionally retain thereon the bobbins B to be wound.

The spindle 15 is normally urged into its operative position, i. e. the position shown in full lines in Fig. 2, by a spring-pressed plunger 19 located mainly within the bore 16^a of the bearing 16 and having its head portion 19^a forcibly engaging the end of the spindle. A coil-spring 20, surrounding the plunger 19 between the head thereof and a wall of the bearing 16 through which the end of the plunger passes, provides the force for shifting the spindle into its operative or bobbin-winding position.

At the completion of a bobbin-winding operation the operator presses against the side of the bobbin and shifts the spindle from its full line

position, Fig. 2, to its dotted line position. This breaks the driving connection between the belt 6 and the disk 18 and aligns an annular groove 21, formed in the spindle 15, with the inner free end 5 22^a of a spring-pressed locking pin 22 slidingly mounted in a side-wall 1^b of the base 1. The instant the groove 21 is aligned with the pin 22 a spring 23, interposed between the side-wall 1^b and a nut 24 threaded on the pin, projects the 10 free end of the pin into the annular groove 21, as shown in Fig. 3, and holds the spindle in its innermost or inoperative position.

Inasmuch as the bobbin must be securely fixed to the tapered end of the spindle during the winding action, it follows that some difficulty may be experienced in removing the filled bobbin therefrom. It has been found that the bobbin may be most readily removed from the spindle by slightly turning it while exerting a lateral pull thereon.

20 To facilitate relative turning between the bobbin and the spindle, this invention provides novel means for locking the spindle against rotary movement, whereby rotation of the bobbin by the operator will free it from the spindle. This locking means comprises a socket 25 (see Figs. 2 and 3) formed in the spindle 15 intermediate the walls of the annular groove 21 and into which the free end 22^a of the spring-pressed locking pin 22 snaps (see Fig. 4) when the spindle is slightly rotated 25 after it has been shifted axially to its inoperative position. The socket is preferably formed as shown in Figs. 3 and 4, i. e. with its side walls tapered. This construction provides ready entry for the end of the locking pin and prevents binding between the pin and the walls of the socket while securely locking the spindle against rotation. However, if desired, the socket may be smaller, as indicated at 25^b in Fig. 5 and the end of the locking pin may be tapered as shown at 22^b to snugly 30 engage the side walls of the socket.

To initiate a bobbin-winding operation, an empty bobbin is placed upon the tapered end of the spindle preferably with a slight turning motion which frictionally binds the bobbin thereon. 45 The operator then grasps the head 22^h of the locking pin 22 and pulls it outwardly, in opposition to the spring 23, thereby withdrawing the end 22^a of the pin from the locking notch 25 and from the annular groove 21 in the spindle 15. The spring-plunger 19 thereupon shifts the spindle axially and forces the disk 18 into driving contact with the driving belt 6.

50 From the foregoing it will be perceived that this invention has provided an improved and simplified form of bobbin-winder which readily may be thrown into and out of action and which is provided with means for both holding the bobbin-winding spindle in its inoperative position and for locking it against rotation to facilitate removal of the bobbin therefrom.

Having thus set forth the nature of the invention, what I claim herein is:—

1. In a sewing machine having a frame, a shaft journaled therein, a belt-wheel on said shaft and a driving belt engaging said belt-wheel; a bobbin-winder comprising a bobbin-holding spindle rotatably and translatable journaled in said frame, a disk secured to said spindle and adapted to be driven from said belt, spring means acting on said spindle normally tending to shift said disk into contact with said belt, and detent means acting in opposition to said spring means to maintain said disk out of contact with said belt.
2. In a sewing machine having a frame, a shaft

journaled therein, and driving means for said shaft; a bobbin-winder comprising a bobbin-holding spindle rotatably and translatable journaled in said frame and having operative and inoperative axial positions, means effective when said spindle is in its operative position to rotate the spindle from said driving means, spring means acting on said spindle normally tending to shift it into its operative position, and manually controlled detent means acting in opposition to said 5 spring means to maintain said spindle in its inoperative position.

3. In a sewing machine having a frame, a shaft journaled therein, a belt-wheel on said shaft and a driving belt engaging said belt-wheel; a bobbin-winder comprising a bobbin-holding spindle rotatably journaled in said frame and axially movable therein substantially parallel with said shaft from operative to inoperative positions, a disk secured to said spindle and adapted, in the operative position of said spindle, to be driven from said belt, a spring plunger acting on one end of said spindle and normally tending to shift it into its operative position, and manually controlled means acting in opposition to said spring 15 means to maintain said spindle in its inoperative position and to lock said spindle against turning.

4. In a sewing machine having a frame, a shaft journaled therein and driving means therefor; a bobbin-winder comprising a bobbin-holding spindle rotatably journaled and axially movable in said frame and having operative and inoperative axial positions, means effective when said spindle is in its operative position to rotate the spindle from said driving means, spring means acting on said spindle normally tending to shift it into its operative position, manually controlled detent means acting in opposition to said spring 20 means to maintain said spindle in its inoperative position, and means effective when said spindle is in its inoperative position to lock the spindle against turning.

5. In a sewing machine the combination with a frame, a shaft rotatably journaled therein, a drive-wheel having a bearing on said shaft, means to lubricate said wheel bearing, manually actuated means to secure said drive-wheel to said shaft, and a power driven belt engaging said drive-wheel to rotate the latter; of a bobbin-winder 45 comprising a bobbin-holding spindle supported by said frame and rotatably and axially movable therein, a spindle-driving disk secured to said spindle and adapted to engage said belt, a spring plunger engaging said spindle and normally tending to shift it axially from an inoperative position to an operative position thereby to establish a driving contact between said belt and said disk, manually controlled locking means adapted to prevent said spindle from being moved by said 50 spring-plunger, and means active when said spindle is in its inoperative position to prevent turning of said spindle.

6. In a sewing machine having a frame, a shaft journaled therein and driving means carried by 65 said shaft; a bobbin-winder comprising a rotatable and translatable bobbin-holding spindle mounted in said frame substantially parallel with said shaft, a spindle-rotating disk secured to said spindle and adapted in one of two axial positions 70 thereof to engage said driving means, impulsive means tending to shift said spindle axially to engage said disk with said driving means, and detent means rendered effective when said spindle is shifted to its other axial position to restrain 75

said spindle from movement under the influence of said impositive means.

7. A bobbin-winder comprising a rotatable spindle having a free end adapted to receive a bobbin, means to rotate said spindle to effect a bobbin-winding operation, and means to lock said spindle against rotation to facilitate removal of the bobbin therefrom.

8. A bobbin-winder comprising a rotatable and axially movable bobbin-holding spindle, means including a member on said spindle and a driver therefor for rotating said spindle to effect a bobbin-winding operation, yielding means tending to shift said spindle axially in one direction to an operative position to effect a driving contact between said member and its driver but permitting the spindle to be moved in the opposite direction to an inoperative position, and locking means to hold said spindle in its inoperative position.

20 9. A bobbin-winder comprising a rotatable and axially movable bobbin-holding spindle having operative and inoperative positions, impositive means for shifting said spindle axially from its inoperative position to its operative position, means active when said spindle is in its operative position to rotate the spindle thereby to effect a bobbin-winding operation, manually controlled

means operative in opposition to said impositive means for holding said spindle in its inoperative position, and means effective when said spindle is in its inoperative position to lock it against turning.

5 10. A bobbin-winder comprising a rotatable and axially movable spindle provided with a bobbin-receiving end, an annular groove and a locking socket, said spindle being shiftable axially from operative to inoperative positions, means 10 effective when said spindle is in its operative position to rotate said spindle, impositive means normally tending to shift said spindle to its operative position but permitting it to be shifted manually to its inoperative position, a spring-pressed plunger adapted, when the spindle is shifted to its inoperative position, to enter said annular groove to prevent endwise movement of said spindle and to enter said socket to prevent turning thereof.

15 11. A bobbin-winder as set forth in the preceding claim in which the locking socket is formed in the spindle between the side walls of the annular groove and in which a portion of the spring-pressed plunger extends to the outside of the 25 machine for manipulation by the operator.

RAYMOND L. PLUMLEY.
